NOISE CONTROL SYSTEM

Rogers M. Smith, Merchantville, N. J., assignor
to Radio Corporation of America, a corpora-
tion of Delaware

Application June 29, 1935, Serial No. 29,006

10 Claims. (Cl. 179—171)

The present invention relates to a noise control system for radio receiving apparatus and the like, and has, for its primary object, to provide an improved system of that type which may be applied to an amplifier in a radio receiving system and which, at the same time, is provided with variable control means for limiting the signal amplitude through the amplifier.

It is also an object of the present invention, to provide an improved noise reducing system for radio receiving apparatus and the like which may be included in an audio frequency amplifier and which provides simultaneously, variable control of noise limitation and of the high frequency response of the audio frequency amplifier.

It is a further object of the present invention, to provide an audio frequency amplifier for use in radio receiving systems and the like wherein the overloading point of an electric discharge amplifier device therein may be varied jointly with tone control means through operation of a single variable control device.

The invention will, however, be better understood from the following description when considered with the accompanying drawing and its scope will be pointed out in the appended claims.

In the drawing, Figure 1 is a schematic circuit diagram of a radio receiving system embodying the invention;

Fig. 2 shows a series of curves illustrating an operating characteristic of the system in Fig. 1, and

Fig. 3 is a schematic diagram showing a modification of the circuit of Fig. 1.

Referring to Fig. 1, the radio receiving system, represented therein, comprises a radio receiver and detector indicated by the block diagram 5 having a radio signal input circuit represented by the antenna and ground leads 7 and having an audio frequency output circuit 9.

The audio frequency output circuit is coupled through a coupling condenser 11 and grid leak resistor 13, to an audio frequency amplifier stage comprising a tube 15 having a cathode 17, a control grid 19, a screen grid 21 and an output anode 23.

The control grid 19 receives biasing potential from a self-bias resistor 25 through the coupling resistor 13. The output anode 23 and screen grid 21 are connected through circuits 27 and 29 respectively with a variable resistor 31 having a movable contact 33.

The output anode circuit 27 of the amplifier device 15 also includes a suitable output device such as a transformer 35. The contact 33 con-

nected with the circuits 27 and 29 is provided with a by-pass condenser 37 to the cathode.

One terminal 41 of the resistor 31 is connected with any suitable source of positive anode current indicated by the lead +B, the negative anode 5 supply being connected with the lead 39 as indicated at —B. A by-pass condenser is provided across the supply circuit as indicated at 38. Movement of the contact 33 serves to vary the potential applied to the anode 23 and the screen 10 grid 21, thereby to vary the overload point of the amplifier device 15 as will hereinafter appear.

It will be noted that the resistor terminal 43 is connected through a condenser 45 with the output circuit 27 adjacent to the anode 23 and on the 15 anode side of the coupling device 35.

The coupling device 35 is connected with a suitable audio frequency amplifier, indicated by the block diagram 47 and which, in turn, supplies signals to the output device or loudspeaker 49. 20

The operation of the system is as follows: For a given output from the audio frequency amplifier stage comprising the amplifier tube 15, the plate voltage is reduced on the tube by moving the control device in a direction to cause the contact 25 33 to move toward the terminal 43 until a voltage point is reached at which the amplifier stage is on the point of overloading. At this setting of the control 33, static noise or other intermittent signals causing excessively high voltages to be 30 applied to the stage through the signal channel from the receiver, can not exceed the level of the desired signal more than a few percent, where-as it would ordinarily exceed the signal many times in amplitude.

The variable control element or resistor in the anode circuit of the amplifier serves to vary the overloading point of the amplifier tube by varying the plate voltage. Movement of the contact 33 as described serves to reduce the voltage to a 40 point such that the amplifier may operate near the knee of a characteristic curve plotted between power output and plate voltage. Operating curves of this type are shown in Fig. 2 to which attention is also directed.

In Fig. 2 various desired points for operating the amplifier are indicated at 51, 53 and 55 on power output-plate voltage curves 57, 59 and 61, respectively. For example, curve 57 corresponds to an adjustment of the contact 35 near the 50 terminal 41, and curve 61 corresponds to an adjustment to the point 43. It will be noted that each of the points 51 to 55 are located near the knee of the characteristic curve whereat further increases in amplifier voltage may cause no 55

appreciable increase in the amplifier power output. Since static signals, for example, are generally of greater amplitude than the desired signal, the static signals are limited to practically the same power output level as the signals. Therefore, operating the amplifier tube on the knee of its plate voltage-power output curve causes it to act as a cut-off or noise limiting device.

When the control device 31-33 is operated to cause the contact 33 to approach the terminal 43, it will be noted that the resistance element in series with the condenser 45 is reduced, thereby causing the condenser to load the output coupling device 35, maximum loading occurring when the contact 33 reaches the terminal 43. At this point also, the anode current is reduced to the lowest limit.

With this arrangement, since capacity loading occurs, with an inductive or resistive coupling system, high frequency response and static noises, composed chiefly of high frequency components, are further reduced by this reaction.

The static limiting system described depends, therefore, on the overloading characteristics of an electric discharge amplifier tube when used as an audio frequency amplifier, and upon capacity loading across an audio frequency transmission circuit including inductance or other plate load used in the tube plate circuit. For coupling purposes, the overloading feature is made variable as well as the capacity loading, by means of a single resistor device 31-33 connected as a potentiometer and providing two functions simultaneously with one variable control element 33.

With the circuit arrangement shown, minimum static response with reduced output and high frequency response is provided, when the control element 33 is at the end 43 of the resistor 31 providing maximum resistance and maximum shunt capacity load across the normal anode circuit load, while full gain without noise reduction and without reduction in high frequency response is obtained when the contact 33 is moved to the terminal 41. At intermediate points between the terminals 41 and 43 any degree of static reduction and output control may be obtained, the amplifier operating at the knee of a characteristic curve such as those shown in Fig. 2 for differing adjusted anode or screen potential.

Referring now to Fig. 3, the amplifier tube of Fig. 1 is shown directly connected to the loudspeaker 49 without the intermediary of an audio frequency amplifier. Also, the screen grid potential is made variable while the anode potential is fixed. The remainder of the circuit is the same as in Fig. 1, and like parts throughout and circuit leads bear the same reference numerals as in Fig. 1.

The tube 15 utilized as an output audio frequency amplifier is coupled through a suitable step-down transformer 51 with the loudspeaker device 49, the loudspeaker load being transferred to the anode circuit 21. The loading device 45 and the variable means 31-33 provide a variable load means for the output circuit of the amplifier tube, the load circuit being completed through the by-pass condensers 37 and 38.

It will be noted that the anode circuit is returned to the positive supply lead +B through a lead 53. The screen grid circuit 29 is connected with the variable contact 33 whereby as the contact is moved along the resistor 31 toward the terminal 43 the screen grid potential is reduced and the shunt load across the output coupling device 51 is increased.

It will thus be seen that the output amplifier tube may be controlled by varying the screen potential thereby to limit the power output, the relation between the screen grid voltage and the power output being such that the amplifier tube operates near the knee of its power output screen voltage curve, the curves in Fig. 2 indicating substantially the operating characteristics of the circuit of Fig. 3 as well as that of Fig. 1.

A variable means for simultaneously controlling the power output characteristic and the audio frequency response characteristic of an output audio frequency amplifier stage for noise suppression has the advantage that the noise response is reduced at the output end of the signal amplifying channel so that any noises developed in preceding circuits may also be removed just prior to the application of the output signals to the sound producing device.

As in the circuit of Fig. 1, the power output of the amplifier is variably controlled simultaneously with the output circuit loading which includes a frequency discriminating device such as the tone control condenser shown. In a power amplifier it is desirable that the power circuit be complete and for this reason the control of the screen potential alone is preferable, particularly where the power output is relatively high and the anode current is correspondingly increased.

I claim as my invention:

1. The combination with an audio frequency amplifier including an electric discharge amplifier tube, of means for applying a self-biasing potential thereto, means providing an output coupling impedance therefor, means providing a frequency discriminating variable network in connection with said impedance, and means for applying an operating potential to an electrode of said device adapted to limit the power output thereof, said means including a circuit connected through said variable network whereby said potential is simultaneously variable therewith.

2. An audio frequency amplifier for a radio receiving apparatus and the like having a power output stage comprising an electric discharge amplifier device, an output coupling device therefor, a load circuit connected therewith whereby the load is reflected into the output circuit of said device, means providing an auxiliary frequency discriminating load for said amplifier device in connection with the output circuit thereof, and common means for simultaneously varying a potential on one of the electrodes of said device and said auxiliary load.

3. In an audio frequency amplifier, the combination of an output electric discharge amplifier device having a screen grid, a control grid, an output anode and a cathode, a sound producing device, means for coupling said sound producing device to said anode, and means for simultaneously varying the power output of said amplifier device and the frequency response characteristic of said amplifier stage comprising a variable resistance device in circuit with the screen grid, a reactance device connected in shunt relation to said output coupling device through said variable resistance device whereby the loading effect thereof on the output circuit of said amplifier device is simultaneously controllable with said screen grid potential.

4. In an audio frequency amplifier, the combination with an electric discharge amplifier device, of means providing a signal input circuit therefor, and means connected with the output circuit for varying the anode potential thereby.

- to cause the device to operate on the knee of its power-output plate-voltage characteristic curve, and means for variably loading the output circuit connected with said variable means for simultaneous control therewith.
5. In a radio receiving system, an audio frequency amplifier adapted to operate in conjunction with a screen grid amplifier tube and comprising an input circuit for said tube, means for applying a biasing potential to said input circuit, an output circuit therefor including an anode circuit load element, a condenser connected with said output circuit in shunt relation to said load element, a variable resistance device connected 10 in circuit with said condenser and having a movable contact for controlling both the anode and screen grid potentials for said tube, said variable resistor device being so connected in circuit with said condenser that said condenser is gradually connected directly in shunt with said load element as the anode and screen grid potentials are gradually reduced to a minimum by operation of said variable resistor device.
6. In a radio receiving system, the combination with an audio frequency amplifier, of an electric discharge amplifier device having an anode circuit, an audio frequency coupling device in said anode circuit, a variable resistance device connected with said anode circuit to control the operating anode potential applied thereto, means providing a frequency discriminating load connected in shunt relation to said coupling device in said anode circuit and having a connection with said variable resistor whereby the connection with said coupling device is simultaneously variable with the anode potential by said variable resistance device.
7. An audio frequency amplifier for radio receiving apparatus and the like including in combination a screen grid electric discharge amplifier device, means for applying a self-biasing potential thereto, an output circuit therefor including means providing an output load, means providing an auxiliary load for said circuit, and single control means for simultaneously varying a positive operating potential for said device and applying said auxiliary load to said circuit

whereby the auxiliary load increases as the operating potential is reduced in value.

8. In a radio receiving system, means for reducing the power output and audio frequency response of said system to predetermined desired signal levels whereby noise response above said levels is prevented, said means including an audio frequency amplifier stage including a screen grid electric discharge amplifier tube, an output coupling impedance therefor, a tone control condenser connected in shunt relation to said impedance, a variable resistance device in said connection, and a circuit for supplying a positive operating potential to at least one of the electrodes of said device connected in circuit with 15 said variable resistance device whereby said potential and the effect of said condenser in said circuit are simultaneously controllable by a single means.

9. In a radio receiver, a noise limiting system 20 including, in combination, an audio frequency amplifier tube, an output circuit therefor including an output load device, means providing an auxiliary shunt load for said device, and single control means connected in said output circuit 25 for simultaneously varying a positive operating potential for said device and causing the auxiliary load to increase as the operating potential is reduced in value.

10. A noise limiting system for radio receiving 30 apparatus and the like including an output audio frequency amplifier stage comprising a screen grid electric discharge amplifier device, means for applying a self-biasing potential thereto, an audio frequency output coupling device therefor 35 providing an anode circuit load, frequency responsive means connected in shunt relation to said load and including a variable control device for varying said load, and means for applying an operating potential to the screen grid of said 40 device through said variable control device whereby the power output of said amplifier stage and the frequency characteristic thereof are simultaneously variable to establish a predetermined output characteristic.
